UNITED STATES PATENT OFFICE.

WALTER LESLIE STADIG, OF ST. FRANCIS, MAINE.

ROTARY SNOW-PLOW AND SNOW-LOADER.

1,348,383.

Specification of Letters Patent. Patented Aug. 3, 1920.

Application filed August 15, 1918. Serial No. 250,075.

To all whom it may concern:

Be it known that I, WALTER LESLIE STADIG, a citizen of the United States of America, and resident of the town of St.

5 Francis, in the State of Maine, in the United States of America, have invented certain new and useful Improvements in Rotary Snow-Plows and Snow-Loaders, of which the following is the specification.

10 The invention relates to improvements in snow plows and snow loaders as described in the present specification and illustrated in the accompanying drawings that form part of the same.

15 The invention consists essentially in the novel arrangement and construction of parts, whereby the snow is rapidly removed from the roadway and conveyed to one side thereof or loaded on to other vehicles to

20 be carted away later.

The objects of the invention are to economize in the matter of expenses incidental to the employment of numerous men to clear the roadways and other surfaces in

25 cities, towns or other places from the accumulations of snow and ice following the storms and snow falls during the winter time, to improve the operation and constructive features of the various parts included

30 in the snow plow, patented in United States under Nos. 1,084,498 and 1,093,493 on January 13th, 1914, and April 14th, 1914, respectively and to add parts to and change some of the arrangements in the said patented

35 invention in order to facilitate the removal of snow to enable the attendants of the machine to work into side snow banks without placing the motive or draft power into the deeper snows, to insure the delivery of

40 the snow raised from the roadway into receptacles or suitable piles, to guide both front and rear sled or trucks with precision so that the cutters may always reach the most advantageous position for engaging

45 with the snow or ice, to increase the speed in the elevation and delivery of the snow and generally to provide a machine that is efficient, durable, and comparatively inexpensive to construct.

50 In the drawings, Figure 1 is a side elevation of the machine.

Fig. 2 is a side elevation showing various parts removed to disclose mechanism not shown in Fig. 1.

55 Fig. 3 is a rear elevation of the machine. Fig. 4 is a front elevation of the machine.

Like numerals of reference indicate corresponding parts in each figure.

Referring to the drawings, the main frame 1 is carried on the sleds 2 and 3, the former 60 2 being the front or guiding sled and the latter 3 being the rear sled which is also equipped with means for turning, so as to direct it to the roadside in particular places.

65 The front sled 2 is here shown as arranged for draft power such as horses, though any power may be used for propelling purposes and said sleds may be in the form of wheel trucks and driven accordingly or the machine may be hauled by a motor driven vehicle, however the set over device illustrated is for a horse drawn machine and for another power changes would necessarily be made.

70 In the form of the invention described the tongue 4 is slidably mounted on the rail 5 at the front of the sled 2, said tongue being firmly secured in the sleeve 6. The reel 7 is pivotally mounted on the sleeve 6 80 and the cable 8 arranged to wind thereon, the ends of said cable being secured at each side of the sled 2, said cable having a sufficient number of turns on the reel 7 to adjust the tongue on the rail 5 and thereby 85 permit the machine to travel in one path and the horses in another, which is very useful in clearing away banks of snow at the side of a road.

75 The reel is turned by the hand wheel 9 90 and the tongue moved to the desired position.

The rear sled 3 is provided with a ring 10 serving as a turntable, said turntable on one side having the rack 11 in arc-shape, 95 similar to a segmental gear.

80 The upper half 12 of the ring or turntable is rigidly secured to the frame 13, the latter being flexibly connected to the main frame 1 as customary and as more fully described 100 in my earlier patent hereinbefore referred to.

85 The upper ring 12 forms the bearing on which the lower ring 10 turns, when the sled 3 is independently guided toward the side or center of a road as the case may be.

90 The hand wheel 14 is operated in turning the rear sled 3 and this wheel is mounted on the upper end of the post 15, which is journaled in suitable bearings 16 and is operatively connected to the flexible joint 17 and 100 through said joint connected to the worm 18 journaled in the bearings 19, said worm

18 coacting with the rack 11 in turning the ring 10 and consequently in swinging the sled 3.

The driving gear shaft 20 is journaled 5 in suitable bearings supported by the frame 1 and is operatively connected to the motor 21.

The beams 22 swing on the shaft 20 and extend in an oblique direction downwardly 10 and at their lower ends terminate in the bars 23 and 24 rigidly secured thereto and on the upper and lower sides respectively.

The bars 23 and 24 are twisted and extend forwardly to meet at 24^a where they are connected to the suspension bars 25 by the pivots 25^a. The bars 24 extend beyond the pivots 25^a and are adjustably secured to the plates 26 in one or other of the vertical slots 26^a, said plates being straight vertical sections 20 of the plow frame 27. The said plow frame 27 projects upwardly and intermediate of its height the eyebolt 77 is secured thereto, the eye 78 being on the inner side. The reach rod 79 having the ring ends 80 and the turnbuckle center 81 is secured at one end to the eye 78 and at the other to the ring bolt 82 secured to the frame of the machine, thus providing further adjustment for the plow frame 27.

30 The upper ends of the bars 25 are pivotally secured to the cranks 28 fixedly mounted on the shaft 29.

The segmental gear 30 is fixedly mounted on the shaft 29 and coacts with the worm 31 operated by the rotation of the shaft 32 controlled by the hand wheel 33, said shaft 32 being journaled in the bearings 34 and 35.

It will now be seen that by turning the hand wheel the worm coacting with said 40 segmental gear will operate said gear and consequently the cranks, thereby raising or lowering the said beams through the said suspension bars.

The bearings 36 are supported at the lower 45 ends of the beams 22 and in these bearings the cutter shaft 37 is journaled.

The cutters 38 are fixedly mounted on the shaft 37 at each side of the machine and are formed of the vanes 39 of considerable 50 length transversely of the machine and in cross section of spider shape, the vanes of one cutter being set centrally in relation to the vanes of the other cutter so as to keep one always in contact with the road.

55 The vanes 39 reach out from their hub 40 in an easy curve and at the end portions 41 are recessed for the knives 42, the latter being bent into the sharpened shoe ends 43 to more readily cut the snow and ice. The 60 knives are secured to the vanes by the bolts 44 and nuts 45.

The central space between the cutters 38 is occupied by the V-plow 46 which is forward in three inclined sections 47, 48 and 49, 65 the central section terminating in the flat

nose 50, to which is attached the bar 51 forming a holder for the chisel diggers or scrapers 52, said bar extending the full width of the plow.

The chisel diggers are secured in said bar 70 holder 51 and at their ends are ground and formed into the sharpened shoe ends 53.

The bar 51 is reinforced at each side by the strut 54 which is secured to the aforesaid 75 plow frame that supports the plow 46.

The cutters 38 are rotated with the shaft 37 and the latter is driven by the chain 55 and sprockets 56 and 57, the latter being mounted on the shaft 37 and the former on the aforesaid gear shaft driven by the motor. 80

This driving mechanism turns the said cutters several hundreds of revolutions per minute, which has the effect of driving great quantities of snow upwardly and for that reason the inclosed chutes 58 are provided, 85 said chutes terminating in flaring and substantially semi-circular delivery hoods 59 reinforced by the heavy plates 60, that extend beyond the hoods at each end and form baffles to protect the machinery from the flying 90 snow and also form rigid supports for other parts of the mechanism.

It is desirable to control the flying snow, which swirls up the chute and by centrifugal force flies off the edge of the hood in great 95 clouds, and in order to direct this cloud of flying snow the deflector plates 61 and 62 are provided the inner plates 61 being pivotally secured to the plates 60 and extending for the complete breadth of the said hoods 100 and at each end terminating in the downwardly hanging flanges 63. The outer plates 62 also extend the complete breadth of the said hoods and terminate the flanges 64, said outer plates 62 being pivotally joined to the 105 inner plates 61.

The brackets 65 stand out from the backs of the inner plates 61, and the brackets 66 stand out from the backs of the outer plates 62.

110 The levers 67 are for operating the inner plates and these levers turn a shaft 68 on which the cranks 69 are fixedly mounted, said cranks being pivotally connected to the brackets 65. The levers 67 are provided with spring pawls 70 engaging in toothed quadrants 71 as customary in such devices.

The outer plates 62 are operated by the cables 72 and chains 73, said cables being secured to the brackets 66 and extending under 115 the pulleys 74, said chains passing through the rings 75 and locking in the slots 76 beneath said rings.

In operating these deflecting plates the said levers 67 are moved until the inner 125 plates assume the desired angle, say slightly above the horizontal, and the said chains and cables are pulled or let out, until the outer plates assume the desired angle, say forming obtuse angles with said inner plates, this will 130

insure the deposit of the flying snow beyond the machine at each side thereof.

In the operation of the invention the machine is drawn along the road to be cleared 5 and the cutters set in motion. The plow in V-form with its chisel cutters cuts the packed snow and directs all the snow in its path into the paths of the cutters which are also working in their own paths cutting their way 10 through the packed snow and by means of their vanes elevating the snow into the chutes, where it ascends and is flung off the edges of the hoods against the deflecting plates and deposited.

15 The particular operations of the several parts have been described in the foregoing explanation of the details, so it is only repetition to again describe how the numerous devices employed do their own work and 20 how they are actuated.

Various changes may be made in the construction of this machine and in its mode of operation without departing from the spirit of the invention so long as they are within 25 the scope of the claims for novelty following.

What I claim is—

1. In a snow plow, a frame supported on suitable running gear, a cutter chamber, a plow supported from said frame, a rotary cutter supported and driven from said frame 30 and situated to the rear of said plow, and a semi-circular hood extending from the rear wall of said chamber and terminating above said plow.

2. In a snow plow, a frame, a pair of 35 rotary cutters, chutes above said cutters, delivery hoods above said chutes, inner deflecting plates hinged at the upper ends of said delivery hoods, outer deflecting plates hinged to said inner deflecting plates, connecting 40 rods and levers governing the positions of said inner deflecting plates, cables and chains governing the positions of said outer deflecting plates, and means for driving said cutters. 45

3. In a snow plow, a frame, running gear supporting said frame and having a front sled and a rear sled, a transverse rail fixedly mounted on said front sled, a draft member slidably arranged on said rail, a reel 50 rotatably mounted above said draft member, and a cable partially wound on said reel and secured at the ends.

4. A snow plow comprising a transversely shiftable front sled, a swinging rear sled 55 having a turntable mounting, an arc-shaped rack on the runner frame and a coacting worm gear on the upper turntable frame, an operating wheel and post flexibly connected to said gear through a universal joint, a body 60 frame supported on said sleds, a plow adjustably secured to said body, rotary cutters and elevators and means for deflecting the snow in its delivery.

Signed at the city of Montreal, Canada, 65 this 23rd day of May, 1918.

WALTER LESLIE STADIG.
